CONTROLLED CARRIER MODULATION

John L. Reinartz, Manchester, Conn., assignor to
Radio Corporation of America, a corporation
of Delaware

Application February 14, 1936, Serial No. 63,823

9 Claims. (Cl. 179—171)

In operating a short wave transmitter, say of the order of five meters, it is often desirable that the carrier be suppressed in the absence of modulating potentials and built up when modulating potentials are applied, and remain on the air until modulation stops. Such systems are particularly desirable in police transmitter work.

If one considers a class "C" stage which is plate modulated by a class "B" modulating system and where the bias for the class "C" stage is obtained from a grid leak resistance, one will have a normal radiophone transmitter.

One type of transmitter known today comprises a plate modulated radio wave amplifier stage operating class "C" and modulated by an audio frequency modulating stage operating class "B". The bias for the grid or grids of the class "C" stage is supplied by a negative bias voltage from a battery and a grid leak resistance. (I have now described a transmitter.)

If one now adds battery bias in series with the grid leak until the plate current goes to zero, the carrier output will also go to zero. Upon modulating, it will be found that because of the increase in plate voltage applied to the class "C" stage, there will again be a carrier which is modulated for every positive half-cycle of modulation.

I find that such a transmitter has a serious defect that results from the fact that during modulation, good operation is obtained on the positive portions of the modulating potential waves, but on the negative half of the modulating potential cycle, the high negative bias on the class "C" amplifier cuts off all of the negative part of the cycle of the modulating potentials.

It occurred to me that this defect could be overcome if a supplemental positive bias could be supplied to the class "C" stage during modulation, and in the interest of simplicity, efficiency and economy, this supplemental positive bias could be drawn from and produced in the class "B" modulator stage. Preferably, the potential is produced in a resistor in the cathode circuit of the class "B" stage.

In order that the added battery bias may be counteracted and therefore allow normal operation of the class "C" stage, the moment that any audio syllable is started, we place in the connection to the filament of the class "B" tubes a resistor of such value that when normal modulation takes place, the voltage drop across this resistor will equal the added battery bias which we added in series with the grid leak so that normal operation of the class "C" stage again takes place

and the carrier is properly modulated and both negative and positive modulation peaks again take effect.

The time factor which will determine how long after an audio syllable has ceased that the carrier will remain on the air, is determined by the size of the capacitor that is shunted across the resistor.

A trial of this idea completely remedied the fault of negative half-cycle cut-off. Instead of there being zero carrier half the time and positive peak modulation the other half of the time, the positive voltage generated by the cathode resistor completely counteracted the negative battery bias and allowed normal operation of carrier and modulation as soon as any audio tone was allowed to strike the microphone. The capacity across the cathode resistor can be chosen to give that time lag desired before the carrier again goes to zero when the microphone is not spoken into.

In describing my invention in greater detail, reference will be made to the attached drawings in which I have shown in Figs. 1 to 6 inclusive, various modifications of my transmitter, each of which includes modulating means, means for suppressing the carrier in the absence of modulating potentials, and means for preventing the class "C" amplifier from being biased to cutoff on the negative portion of the modulating potential cycle.

Fig. 1 shows a typical plate modulated class "C" amplifier tube 2 having its control grid and cathode connected to a source of high frequency oscillations to be modulated. By the expression class "C" amplifier applicant has in mind an amplifier so negatively biased that plate current flows only for a small portion of the positive half of the impressed wave. Plate modulation is used and the modulating voltage is obtained from a class "B" audio amplifier. The audio amplifier comprises two tubes 4 and 6 having their input electrodes coupled to a source of modulating potentials and their anodes coupled to a secondary winding in the plate direct current circuit of the tube 2. The primary winding of the transformer 10 is connected to the anodes of tubes 4 and 6. A point on this primary winding is connected to the cathodes of the tubes 4 and 6 by way of a source B₂ and a resistance R shunted by a condenser C. This resistance R is also included in the grid direct current circuit of tube 2. It is a characteristic of the class "B" audio amplifier that the average plate current is zero, or at least relatively small, in the absence of audio fre-

quency input voltage, and increases in strength as the audio input increases. Hence, the voltage drop across R is substantially zero in the absence of modulating voltage and rises to a relatively large value when the class "B" stage is fully loaded. This voltage drop across R is inserted in the grid circuit of the class "C" amplifier stage in series with the grid biasing means which is usually a bias voltage and grid leak resistance, but may be a source of potential and for convenience has been shown as two batteries B_0 and B_e . The battery B_0 provides the correct operating bias for normal operation when the stage "C" is fully modulated, while the battery B_e is poled to oppose the potential in R and is equal in voltage to the drop across resistance R when the class "B" stage is working at full modulation output. The bias supplied by B_0 and B_e between the grid and cathode of tube 2 in the absence of modulating potentials on the electrodes of the tubes 4 and 6 is of such value as to bias tube 2 for class C operation. The potential drop across R when signals are applied to tubes 4 and 6 is such as to compensate for the negative bias of B_e so that the tube 2 no longer operates as a class "C" amplifier and the negative portion of the modulated carrier wave is no longer cut off in the anode circuit of 2. Thus, it will be seen that when fully modulating, the drop across R just compensates the voltage of the battery B_e and the stage "C" is no longer cut off on the negative portion of the modulating potential cycle, but produces a fully modulated carrier wave output. As the audio frequency input to the class "B" stage is reduced, the drop across R becomes less and the operating bias on the class "C" stage increases until it reaches a maximum value, which is the sum of the two batteries' voltages when the audio frequency excitation is entirely absent. If R is made large enough so that the total voltage of the two batteries is sufficient to bias the class "C" stage to complete cutoff even on the positive peaks of the RF excitation, then the carrier supplied to the antenna will vanish in the absence of audio frequency input to the class "B" stage. As the audio frequency excitation is reduced, the carrier strength is reduced somewhat proportionally so that both carrier and side-bands diminish at the same time as the audio frequency excitation is reduced.

Fig. 2 shows a similar system wherein the normal operating bias is obtained from the grid current flowing through a grid leak R_g , instead of the battery of B_0 in Fig. 1. With full audio frequency input, the drop across resistance R just neutralizes the battery B_e so that the stage operates in the improved fashion so that there is no negative cycle cutoff, but as the audio frequency input is decreased, the total bias on the class "C" stage increases and ultimately cuts off the class "C" output entirely when the audio frequency voltage is entirely absent. In Fig. 2, a single direct current source B_1 replaces the two sources B_1 and B_2 of Fig. 1.

The class "C" stages may be neutralized if desired by connecting a variable condenser C_n between the anode circuit and the grid as shown in Figs. 1 and 2. The modulated wave may be impressed on a line or on a radiating system 20, as shown.

Fig. 3 shows a similar system utilizing a pentode type of output tube 2 with modulation on both the screen electrode 12 and the plate electrode 14. In this case, the bias of the suppressor grid 16, which is the sum of the battery B_e , B_0

voltage and the drop across resistance R , varies between normal value and cutoff value as the audio frequency excitation of the class "B" stage is decreased from maximum to zero.

It will be understood that condenser C in the figures bypasses audio frequency currents so that the drop across resistance R varies with the average audio frequency intensity, the average being taken over a period which increases in proportion to the size of the condenser. Thus, the length of time that will elapse between cessation of audio input and cessation of carrier output will be determined by the size of this condenser.

In practice, the single class "C" stage comprising the tube 2 is often replaced by a push-pull stage comprising tubes 2 and 2' connected as shown in Fig. 4. Here, as in the prior figures, as for example Fig. 2, the potential supplied in the grid leak R_g is supplemented by a potential supplied from B_e and the potential drop in R_1 . The potential drop in R_1 is sufficient to compensate the potential produced by B_e in the presence of full modulation so that the carrier wave linearly modulated throughout the entire modulating potential cycle is obtained. The operation of the arrangement of Fig. 4 will be understood from an understanding of the operation of the prior figures and a detailed description thereof is thought unnecessary at this point.

Instead of using some of the class "B" voltage, as developed across resistance R placed in the cathode lead of the class "B" stage, I may add a tube of proper power size and biased to cut-off or operated class "B", and connect its grid to the class "A" stage driving the class "B" stage. The output of this additional tube is dissipated in a resistance R . The voltage appearing across this resistance is used to overcome the added bias of the class "C" stage as heretofore explained. This method effectively removes any tendency for creating distortion in the class "B" stage.

An arrangement as described briefly in the preceding paragraph has been illustrated in Fig. 5. In Fig. 5, the radio frequency amplifier class "C" stage and the audio frequency amplifier and modulating class "B" stage is similar to those described hereinbefore and a description thereof is believed unnecessary here. It is noted, however, that numerals and letters corresponding to those used in the description of the prior figures have been applied to the tubes in the class "C" stage and the class "B" stage. An additional thermionic tube 30 of the pentode type has its control grid 32 connected as shown by way of a biasing potential source C_b to the control grid of a tube 4 in the class "B" stage. The cathode of the pentode tube 30 is connected to the cathode of tube 4. In this manner, modulating potentials from any source and preferably from a class "A" initial stage supplying transformer 40 is applied to the control grid of tube 30. The anode-to-cathode circuit of tube 30 includes a biasing resistance R shunted by the time element condenser C and a source of anode potential EE . Voltage for the screen electrode 36 may be supplied from any source, such as the source supplying potential to the anodes of the class "C" and class "B" stage. In this arrangement, as in the prior arrangements, the potential produced in R overcomes the added potential B_e in the presence of full modulation, thereby insuring complete modulation of the wave throughout the entire modulating potential cycle. The speed with which this control takes place to change

the carrier on the air and remove the carrier from the air depends on the size of the condenser "C".

5 The tube 30 is biased by C_b to operate class "B". That is to say, tube 40 is biased by C_b to cutoff when no modulation is taking place so that no modulating potentials are supplied to transformer 40 and from 40 to the control grid 32 of tube 30.

10 In a preferred modification, the biasing resistor R and condenser C may be placed in the cathode lead of the tube 30 as shown in Fig. 6. When the resistance R is placed at this point, it is operating nearer ground potential and reduces the 15 precautions necessary with respect to insulation, etc. Fig. 6 is otherwise similar to Fig. 5 and needs no further description.

What is claimed is:

1. In a signalling system, a carrier wave amplifier tube having a grid electrode and a cathode coupled to a source of potentials of carrier wave frequency and output electrodes coupled to a load circuit, a modulator tube having input electrodes coupled to a source of modulating 25 potentials and output electrodes coupled to an electrode of said amplifier tube, biasing means in the direct current grid circuit of said amplifier tube for controlling the gain thereof, and biasing means in a direct current circuit of said modulator tube connected with said first named biasing means to oppose the control thereof in accordance with average modulating potential intensity.

2. In a signalling system, a carrier wave amplifier tube having a grid electrode and a cathode coupled to a source of wave energy and output electrode coupled to a load circuit, a modulator tube having input electrodes coupled to a source of modulating potentials and output electrodes coupled to an electrode of said amplifier tube, biasing means in the direct current circuit between the grid and cathode of said amplifier tube for controlling the gain thereof, said biasing means being sufficient to bias said wave amplifier tube to cutoff in the absence of modulating potentials, and biasing means in a direct current circuit of said modulator tube connected with said first named biasing means to oppose the control thereof in accordance with average modulating potential intensity, said last named biasing means being sufficient to prevent cutoff of said amplifier tube on the negative portion of the modulating potential cycle.

3. In a signalling system, a carrier wave amplifier tube having a grid electrode and a cathode coupled to a source of wave energy and output electrodes coupled to a load circuit, a modulator tube having a grid electrode and a cathode coupled to a source of modulating potentials and output electrodes coupled to an electrode of said amplifier tube, biasing means in a direct current circuit between the grid and cathode of said amplifier tube for controlling the gain thereof, and biasing means in the direct current circuit between the output electrodes of said modulator tube connected with said first named biasing means to oppose the control thereof in accordance with average modulating potential intensity.

4. In combination with an electron discharge amplifier tube having an input circuit coupled to a source of carrier waves and an output circuit coupled to a load circuit, said tube being negatively biased for class C operation, a modulator 75 tube having its input electrodes coupled to a

source of modulating potentials and its output electrodes coupled to an electrode of said discharge tube to modulate the same, said modulator tube being negatively biased for class B operation, a source of potential connected with the input circuit of said first named tube of sufficient value to bias said tube to zero alternating current output in the absence of modulating potentials, a resistance connected between the output electrodes of said class "B" modulator tube, and 10 circuits connecting said resistance in series with said source of potential, said resistance being of such value as to produce a potential sufficient to compensate said source of potential in the presence of modulating potentials. 15

5. In combination with an electron discharge tube having input electrodes coupled to a source of carrier waves and an anode electrode coupled to a load circuit, said tube being negatively biased for class C operation, a modulator tube having its input electrodes coupled to a source of modulating potentials and its output electrodes coupled to the anode electrode of said discharge tube to anode modulate the same, said modulator tube being negatively biased for class B operation, 25 a source of potential connected between the input electrodes of said first named tube of sufficient value to bias said tube to cutoff in the absence of modulating potentials, a resistance connected between the output electrodes of said modulator tube, and circuits connecting said resistance in series with said source of potential, said resistance being of such value as to produce a potential sufficient to substantially buck out said cutoff potential in the presence of modulat- 30 ing potentials. 35

6. In combination with an electron discharge tube having a control grid and cathode coupled to a source of carrier waves and an anode and cathode coupled to a load circuit, said tube being negatively biased for class C operation, a modulator tube having its input electrodes coupled to a source of modulating potentials and its anode electrode coupled to the anode electrode of said an electron discharge amplifier tube to 40 modulate the same, said modulator tube being negatively biased for class B operation, a source of potential connected between the control grid and cathode of said first named tube of sufficient value to bias said tube to zero alternating current output in the absence of modulating potentials, a resistance connected between the anode and cathode of said modulator tube, and circuits connecting said resistance in series with said source of potential, said resistance being of 45 such value as to produce a potential sufficient to overcome said source of potential in the presence of modulating potentials. 50

7. In a signalling system an electron discharge tube, a source of waves to be modulated connected to the input electrodes of said tube, a load circuit coupled to the output electrodes of said tube, a modulator tube, a source of modulating potentials connected with the input electrodes of said modulator tube, circuits connecting a pair 65 of electrodes of said discharge tube together and coupling the same to electrodes in said modulator tube, means for supplying a biasing potential to said first named tube to bias the same to cutoff when no modulating potentials are applied to 70 said second named tube, means for producing in a direct current circuit of said second tube a potential which is a function of the mean amplitude of applied modulating potentials, and circuits connecting said first named means to said 75

last named means in a manner such that said potentials oppose.

8. In a signalling system a pair of electron discharge tubes each having input and output electrodes, a source of waves to be modulated connected to the input electrodes of said tubes, a load circuit coupled to the output electrodes of said tubes, a pair of modulator tubes each having input and output electrodes, a source of modulating potentials connected with the input electrodes of said modulator tube, circuits connecting similar electrodes in said discharge tubes together and coupling the same to like electrodes in said modulator tubes, means for supplying a biasing potential between the input electrodes of said first named pair of discharge tubes to bias the same to cutoff when no modulating potentials are applied to said second named pair of tubes, means for producing in a direct current circuit between the output electrodes of said second named pair of tubes a potential which is a function of the amplitude of applied modulating potentials, and circuits connecting said first named means to said last named means in a manner such that said potentials oppose.
9. In a signalling system a pair of electron

discharge tubes each having an anode, a cathode and a control grid, a source of waves to be modulated connected to the cathodes and control grids of said pair of tubes, a load circuit coupled to the anode and cathode electrodes of said pair of tubes, a pair of modulator tubes each having an anode, a cathode and a grid electrode, a source of modulating potentials connected with the grid and cathode electrodes of said pair of modulator tubes, circuits coupling similar electrodes in said discharge tubes to similar electrodes in said modulator tubes, resistive means for supplying a biasing potential between the grid and cathode of the tubes of said first named pair of tubes to bias the same to cutoff when no modulating potentials are applied to said second named pair of tubes, means for producing in a direct current circuit between the anodes and cathodes of the tubes of said second named pair of tubes a potential which is a function of the amplitude of applied modulating potentials, and circuits connecting said first named means to said last named means in a manner such that said potentials oppose.

JOHN L. REINARTZ. 25
